TYPE-WRITING MACHINE.

Patented Jan. 17, 1911.

981,895.

Specification of Letters Patent.

Application filed October 17, 1908. Serial No. 458,242.

To all whom it may concern:

Be it known that I, FRANZ PAUL STRAUSS, engineer, a subject of the German Emperor, and resident of Frankfort-on-the-Main, in 5 the Kingdom of Prussia, German Empire, with the post-office address Kettenhofweg No. 217, have invented new and useful Improvements in Type-Writing Machines, of which the following is a specification.

- 10 Typewriting machines are known in which longitudinally movable type bars are arranged in a horizontal plane radially to the printing point. In practical use this class of typewriters has been shown to 15 possess the disadvantages that the characters must be made very small in consequence of the narrow space available for them, so that the employment of large characters is rendered difficult. Furthermore the number 20 of the characters cannot be increased above 90 without a further decrease of their width, whereas an increase in the number of characters is desirable and even necessary in the 25 Slavonic languages, because the alphabets of these languages contain more letters than, say, the Latin alphabet. It has therefore 30 been attempted to construct typewriting machines having as large, and as many characters, as possible in order that they might 35 be used for the various purposes in the different languages, and possessing, besides, as large a printing power as possible so as to be able to obtain a large number of copies. These advantages could be attained for typewriting machines provided with type bars 40 of the kind mentioned above, by removing the characters farther from the printing point until the arc in which the type is arranged around the printing point is increased so far that sufficient space for an 45 increase in number and width of the characters would be available. There are, however, obstacles to this simple expedient, because the shifting of the characters away 50 from the printing point for one unit lengthens and broadens the whole type set with its type bars to three times this unit. Hence the whole typewriter would assume such an unusual size that its practical and convenient use would be seriously affected.

The object of the present invention is to avoid these difficulties, and to this end each type bar is guided horizontally upon a radially slotted plate, which is in only half

the length of the stroke of the type bars. 55 Besides this the well known movement, consisting of a bent double arm type lever and a crank lever, is used. The short guide plate only serves to guide the type bar in a horizontal direction during the last part 60 of the stroke, in which the known tail-piece fixed to the type bar is guided upon this slotted plate. The tail-piece however can be made much shorter than hitherto usual so that even if one more row of keys be 65 used, the machine becomes scarcely longer than before. Furthermore the arrangement is made such that the driving lever does not extend through the slotted plate and is guided in this as in known constructions, 70 but the guide block of the type bar extends downwardly through the corresponding slot of the slotted plate and thus is radially guided. The end of the tail-piece of the 75 type bar is provided with a head, an enlargement, or the like, running on the slotted plate and thus preventing the type bar from falling downwardly.

The invention is illustrated in the accompanying drawings, wherein— 80

Figure 1 shows the operating mechanism for the type bars in longitudinal section. Figs. 2 and 3 show the guide of the type bars with the levers operating the latter, in cross-section according to the lines A—B 85 and C—D of Fig. 1. Fig. 4 shows the operating mechanism in plan in its radial arrangement, together with the slotted guide plate.

When the key 1 (Fig. 1), is depressed, the 90 key lever 2 turns upon its pivot 3. As the lever 2 slides with its pivot in the forked end 5 of the intermediate lever 4, this lever when the key is depressed simultaneously swings 95 around the pivot 6, so that the type bar 7 carrying a type block 8 and engaging with the pivot 18 into a forked end of the type bar 7 is thrown against the platen 9, while the return into the position of rest is effected by means of a spring 10. This mechanism 100 however is known in the art.

The guiding of the type bars is effected by means of a guide plate 11 radially slotted from 22 to 23. The upwardly extending front comb 22 effects the lateral guiding 105 wherein it is aided by the guide blocks 24 of the type bars extending downwardly through the slots, whereas the non-slotted

rear end 23 serves as horizontal guide. The horizontal guiding of the type bar will take place until the end 25 passes, when thrown forward, the non-slotted part 11 of the guide 5 plate. In this movement, the type bar would ordinarily fall with its rear end into the slot 26. In order to prevent this, the end of the type bar is bent in a suitable manner, for instance into an eye 25, so that this portion, 10 being broader than the slot 26 effects the further guiding until the end of the movement. The length of the slot 26 in the plate 15 from 22 to 23 is necessary in order to keep the forked end 24 of the type bar free. In this manner it is possible to keep the ends 20 of the type bars as short as possible so that with an increase in the number of the characters, the machine does not attain too large proportions. The eyes 25 can at the same time serve for the purpose of engaging a locking comb known *per se*, for the purpose of locking the type bars when replacing all the set by another one.

Now what I claim and desire to secure 25 by Letters Patent is the following:

1. In a typewriting machine, a guide plate provided with radial slots, horizontally arranged type bars provided with portions arranged to enter the slots and having at 30 their rear ends laterally extended portions to prevent the ends from falling through the slots and means for operating the type bars.
2. In a typewriting machine, a guide plate provided with radial slots, horizontally ar-

ranged type bars provided with portions 35 arranged to enter the slots and having at their rear ends bent portions to prevent the ends of the bars from dropping through the slots and means for operating the type bars.

3. In a typewriting machine, an elevated 40 guide plate provided with radial slots, horizontally arranged type bars having their ends extended laterally to prevent them from falling through the slots and means beneath the guide plate for operating the 45 type bars.

4. In a typewriting machine, a guide plate provided with radial slots and with upwardly projecting portions at its front edge, horizontally arranged type bars provided 50 with depending forks arranged to enter the radial slots in the plate, the bars themselves passing between the upwardly extended portions at the front edge of the plate to hold them laterally in position, said bars being 55 further provided with laterally extended rear ends to prevent them from falling through the slots in the plate and means for operating the bars.

In testimony, that I claim the foregoing as 60 my invention, I have signed my name in presence of two witnesses, this first day of October 1908.

FRANZ PAUL STRAUSS.
